Louis A. Lupien Inventor
By his Attorney Frank M. Neur

UNITED STATES PATENT OFFICE.

LOUIS A. LUPIEN, OF BROOKLYN, NEW YORK, ASSIGNOR TO EDWIN B. STIMPSON COMPANY, OF BROOKLYN, NEW YORK.

CONTAINER OR BOX.

Application filed July 12, 1924. Serial No. 725,581.

This invention relates generally to the construction of containers or boxes formed of heavy paper stock and of a type adapted to be shipped in flat or unfolded condition and to be folded and fastened into container form as needed.

The invention consists in the provision of a container structure of the general type referred to having a special form of fastening means adapted to be attached to the container blanks and to occupy a flat and out-of-the-way disposition thereon to facilitate shipment and storage of the blank in unfolded or disassembled condition.

Another feature of the invention consists in the construction of the fastening means which includes a pronged member having an eye at one end and with the prong members lying in a side-by-side relation in the same plane when in inoperative condition. The pronged member thus provided is adapted to be held in flat engagement with a surface of the container blank by means of a smaller clip or rivet passed through the material of the blank and through the eye of the main clip member. In order to utilize the pronged member for fastening the blank into position to form a container, the edge portions provided with the clips are bent or folded into overlapping relation at the corners whereupon the prongs of the clip are bent outwardly, passed through openings formed for the purpose in the adjacent flap and clinched into holding relation thereto.

Other features of the invention will be hereinafter referred to.

In the drawings, in which a preferred form of the invention is included,

Figure 1 is a view in perspective of a container constructed in accordance with the invention.

Figure 2 is a plan view of a fastener or clip member forming part of the invention.

Figure 3 is an edge view of the clip member shown in Figure 2.

Figure 4 is a plan view of a modified form of clip member forming part of the invention.

Figure 5 is a plan view of still another form of clip member that may be used as part of the invention.

Figure 6 is a view in perspective of the clip member shown in Figure 2 with an anchoring clip member mounted in the eye thereof.

Figure 7 is a view in perspective of the clip member shown in Figures 2 and 6 in holding relation to the container structure.

Figure 8 is a view similar to Figure 7 showing the fastener prong members in a modified holding position.

Figure 9 is a plan view of a container blank equipped with fastener devices such as are shown in Figure 2.

Figure 10 is an edge view of the container blank shown in Figure 9.

Fig. 11 is a section on line 11—11 of Fig. 1.

Fig. 12 is a section on line 12—12 of Fig. 11.

Fig. 13 is a perspective showing the fastener 18 before it is placed in position.

Referring to the drawings for a more detailed description of the invention, a container blank 10 is shown in Figure 9 which can be folded along the dotted lines 11 and 12 to form a rectangular container or box 13 such as is shown in Figure 1. The container 13 is provided with overlapping corner flap members 14 which not only provide a reinforced corner construction but, in addition, serve to receive fastener members which are used to fasten or attach the overlapping flap members together.

A suitable form of fastener for the purpose is shown in Figure 2. The fastener 15 is provided at one end with an eye-opening 16 and has a pair of prong members 17 extending away therefrom in a side-by-side relation in the same plane.

In practice a set of the fasteners 15 is attached to a blank 10 as in Figure 9 by means of relatively smaller anchoring clip members 18 which are passed through holes formed for the purpose in the blank. The anchoring clip members are provided with inconspicuous heads which are presented at the outer surface of the complete container as in Figure 1. The prongs of the anchoring clip members 18 are passed through the eyes 16 of the fastener members 15 and clinched into a relatively flat relation to the fastener and to the surface of the blank as is clearly shown in Figure 9.

It will thus be seen that the fastener members occupy a flat relation in close engagement with the surface of the blank so that the blanks can be compactly piled without waste space for shipment and storage before use.

The blanks 10 are also provided with per-

forations 19 so disposed as to register with the fasteners 15 on the adjacent side wall of the blank when the blank is folded into its final container form. The perforations have 5 an elongation at right angles to the adjacent edges of the blank to accommodate the width of the fasteners. When in use the prongs 17 of the fasteners are passed through a perforation 19 and bent apart in opposite directions as is shown in Figures 1 and 7, to hold the overlapping corner flap members 14 in place.

In Figure 8 of the drawing the prong members 17 are twisted as at 20 to prevent the withdrawal of the prongs through the perforation.

In Figure 4 of the drawing the edges of the prongs 17 of the fastener are provided with serrations 21 having abrupt edges 22 20 to prevent withdrawal of the prongs through the perforations and to thereby hold the container firmly in erect position.

In Figure 5 a somewhat similar construction is shown in which the prongs 17 have 25 their edges provided with rounded notches 23 to provide serrations for a like purpose.

What I claim is:—

1. As an article of manufacture, a container blank adapted to be formed into a box, fastener members formed of sheet metal 30 and provided with an eye opening at one end, said fastener members including prong members extending in a side-by-side relation in the same plane, and anchoring members 35 passing through the blank and the eye openings to hold the fastener member in a flat disposition on a surface of the blank until used to hold the blank in folded container form the anchoring members being visible 40 from the exterior when the blank is in fold-

ed form, the prongs being adapted to hold the box in assembled relation by extending through apertures in the blank and by being spread beyond the aperture.

2. As an article of manufacture, a container blank adapted to be folded into a box, 45 said blank having flat member extensions arranged when folded to provide a flap overlapping each side adjacent a corner of the box, fastener members formed of sheet metal and provided with an eye opening at one end, said fastener members including prong members extending in a side-by-side relation in the same plane, and anchoring members 50 passing through the flap members of the blank and the eye openings to hold the fastener members in a flat disposition on the blank until the blank is folded into container form, said anchoring members being visible from the exterior of the resulting 55 box, the prongs being adapted to hold the box in assembled relation by extending through apertures in the blank and by being spread beyond the aperture.

3. As an article of manufacture, a container blank having two adjacent side portions, each side portion having attached thereto a flap adapted to overlap the adjacent side when the blank is in folded position, one of said sides having a hole therethrough, a second hole formed in the flap attached to said side, the second side portion having a pronged fastener secured thereto in flat condition and adapted for cooperation with said second hole, and a pronged fastener secured 70 in flat condition to the flap attached to said second side and adapted for co-operation with said first-named hole.

In testimony whereof I affix my signature.

LOUIS A. LUPIEN.
